UNITED STATES PATENT OFFICE.

LADOVICE DANIEL REECE, OF DES MOINES, IOWA.

SAW-HANGER.

940,728.

Specification of Letters Patent. Patented Nov. 23, 1909.

Application filed January 25, 1908. Serial No. 412,676.

To all whom it may concern:

Be it known that I, LADOVICE DANIEL REECE, a citizen of the United States of America, and resident of Des Moines, Polk county, Iowa, have invented a new and useful Saw-Hanger, of which the following is a specification.

The object of this invention is to provide improved means for hanging or suspending a hand-saw in such manner that it can be removed and replaced conveniently.

My invention consists in the construction, arrangement and combination of elements hereinafter set forth, pointed out in my claims and illustrated by the accompanying drawing, in which—

Figure 1 is a front elevation of my improved device, having a saw suspended therein, Fig. 2 is a cross sectional elevation of the holder, and Fig. 3 is a top view thereof.

Referring more particularly to said drawings, my improved device consists of a box having an end wall 1, side walls, 2 and 3, an outer end wall or flange on each side wall, longitudinal flanges 4 and 5 in converging planes and spaced apart to form a V-shaped slot 6. Rollers 7 and 8 are contained in the box and covered by tubes 9 and 10 made of yielding, compressible, elastic material such as rubber. The box is mounted on a suitable support by fastening means, not shown, extended through holes 11 in the end wall 1. The rollers rest loosely in the box with their

tubes in contact and on or above the flanges 4 and 5. The side walls 2 and 3 are on converging planes and cause the rollers to tend by gravity toward each other.

In operation, a saw *a* is projected upwardly through the slot 6, to separate and project between the rollers 7 and 8. After having been extended between said rollers a sufficient distance, the saw is released, whereupon the saw becomes jammed between the rollers, due to their frictional contact therewith, with sufficient force to support the same.

I claim as my invention:—

A saw hanger composed of a box having converging side walls, an end wall, a flange on each side wall, which flanges extend inwardly, and longitudinal converging flanges which extend upwardly from said flanges of the side walls, and a pair of rollers arranged in said box above the inner ends of said converging flanges, said rollers being loosely arranged in said box and being normally in frictional contact with each other and in contact with the respective converging walls of the box.

Signed by me at Des Moines, Iowa, this twenty-second day of January, 1908.

LADOVICE DANIEL REECE.
